UNITED STATES PATENT OFFICE

121,813

DESIGN FOR A SOAP DISH

Stanley Isenberg, Chicago, Ill.

Application April 3, 1940, Serial No. 91,432

Term of patent 14 years

To all whom it may concern:

Be it known that I, Stanley Isenberg, a citizen of the United States and resident of Chicago, in the county of Cook and State of Illinois, have invented a new, original, and ornamental Design for a Soap Dish, of which the following is a specification, reference being had to the accompanying drawing, forming a part thereof.

Fig. 1 is a view in perspective of a soap dish, showing my new design.

Fig. 2 is a side elevational view of the same.

Fig. 3 is a top plan view of the same.

I claim:

The ornamental design for a soap dish, substantially as shown.

STANLEY ISENBERG.
